UNITED STATES PATENT OFFICE.

JAMES J. WOLSELEY, OF BRIDGEPORT, CONNECTICUT.

TOY.

Application filed May 27, 1925. Serial No. 33,209.

To all whom it may concern:

Be it known that I, JAMES J. WOLSELEY, a citizen of the United States, residing at Bridgeport, in the county of Fairfield and State of Connecticut, have invented new and useful Improvements in Toys, of which the following is a specification.

This invention relates to improvements in toys and contemplates the provision of a wheel and handle therefor, the wheel having spring wires upon the inner side of the felly and carrying balls upon their outer ends while the handle has mounted upon one side a bell in juxtaposition to the balls whereby upon the successive revolutions of the wheel the balls will be brought into selective contacting and knocking engagement with the bell.

Another object of my invention is the provision of a pair of relatively flat spring plates arranged upon opposite sides of the bell and in the path of movement of the knobs or balls arranged upon the outer free ends of the spring wires or strips and which when so contacting with the flat spring will be caused to bend with the spring wires or strips and when releasing the said balls therefrom it will be noted that a very hard and quick knock will be given or exercised upon the bell whereby the bell will vibrate and ring to its capacity.

With the above and other objects in view, the invention further includes the following novel features and details of construction, to be hereinafter more fully described, illustrated in the accompanying drawings and pointed out in the appended claims.

In the drawing:

Figure 1 is a side elevation of my invention.

Figure 2 is a horizontal section taken through the wheel and showing the associations of the handle therewith.

Figure 3 is a vertical sectional view taken on line 3—3 of Figure 1 and showing the relative arrangement and the contacting relation of the balls with the flat springs and bell respectively.

Referring to the drawing in detail, where-in like characters of reference denote corresponding parts, the reference character 10 indicates a relatively large wheel which is preferably constructed of light and cheap material and which may be either an artillery or disk wheel and which has con-

nected therewith a handle 11 through the instrumentality of an axle 12.

Arranged upon the inner sides of the handle 11 and in juxtaposition thereon with respect to the inner side of the wheel 10 is a substantially U-shaped member 13 which is secured thereto through the instrumentality of a bolt 14 which also secures a bell 15 to the outer side and within the spaced parallel legs of the U-shaped member 13. The arms of this U-shaped member 13 are relatively flat and resilient. Arranged upon the inner side of the wheel 10 and upon the felly thereof is a plurality of spring wires or strips 16 and balls 17 upon the outer free ends thereof.

In the mode of operation of the present invention it is clearly apparent that when the operator grasps the handle 11 and shoves or pushes the same forwardly or in a reverse movement will cause the wheel 10 to rotate upon its axle 12 and in so doing the balls 17 carried upon the outer free end portions of the spring wires or strips 16 will be brought into selective engagement with the spaced parallel arms of the U-shaped member 13 and in so doing will bend its legs inwardly toward the bell 15 while the spring wires or strips 16 will be bent accordingly and therewith and after the wheel has passed this portion of the U-shaped member 13 it will be noted that a strong spring action of the ball 17 against the bell 15 will be had owing to the resilient character of the spaced parallel arms and spring wires or strips 16 and the bell will ring to its highest capacity owing to the double action of resiliency upon the balls 17.

The invention is susceptible of various changes in its form, proportions and minor details of construction and the right is herein reserved to make such changes as properly fall within the scope of the appended claims.

Having described my invention what is claimed is:

1. A toy of the character described comprising a wheel, a handle pivotally secured to one side of the wheel axle, a bell secured to the inner side of the handle and in juxtaposition with the corresponding side of the wheel felly, a pair of spring members arranged upon the handle upon diametrically opposite sides of the bell, and a plurality of spring wires extending outwardly from the

inner sides of the wheel felly and carrying balls upon their outer free ends and adapted for selective engagement with the spring members and bell respectively.

- 5 2. A toy of the character described comprising a wheel, a handle secured to one side of the wheel hub and axle, a substantially U-shaped flat spring secured to the inner side of the handle and in juxtaposition to the inner side of the wheel felly, a bell secured to the U-shaped flat springs and be-

tween the spaced parallel arms thereof, and a plurality of spring wires including balls upon the outer free ends thereof extending outwardly from one side of the wheel felly 15 and upon the corresponding side with the relatively flat U-shaped spring member and bell and adapted for selective engagement with the springs and bell upon the successive revolutions of the wheel. 20

In testimony whereof I affix my signature.
JAMES J. WOLSELEY.
